UNITED STATES PATENT OFFICE.

FRANK COLLINS, OF NEW YORK, N. Y., ASSIGNOR TO SUNSET LIGHTING FIXTURE COMPANY, INC., OF NEW YORK, N. Y., A CORPORATION OF NEW YORK.

DESIGN FOR A LAMP BASE.

Application filed April 24, 1924. Serial No. 9,380. Term of patent 3½ years.

To all whom it may concern:

Be it known that I, FRANK COLLINS, a citizen of the United States, and a resident of the city, county, and State of New York, have invented a certain new, original, and ornamental Design for Lamp Bases, of which the following is a specification, reference being had to the accompanying drawing, forming part thereof.

In the drawing:

Figure 1 is a top plan view;
Figure 2 is a side elevation; and
Figure 3 is an end elevation.

I claim:

The ornamental design for a lamp base, as shown.

FRANK COLLINS.
